UNITED STATES PATENT OFFICE.

FREDERICK REUTTER, OF WATERBURY, CONNECTICUT, ASSIGNOR, BY MESNE ASSIGNMENTS, TO HENRY GOODFRIEND, OF CHICAGO, ILLINOIS.

SHADE-HOLDER.

1,114,522.

Specification of Letters Patent.

Patented Oct. 20, 1914.

Application filed April 25, 1914. Serial No. 834,350.

To all whom it may concern:

Be it known that I, FREDERICK REUTTER, a citizen of the United States, and a resident of Waterbury, in the county of New Haven and State of Connecticut, have invented a new and Improved Shade-Holder, of which the following is a full, clear, and exact description.

This invention relates to shade holders of that type disclosed in United States Letters Patent Number 1039519, granted September 24, 1912, to Henry Goodfriend, such shade holder being characterized by the provision of an inwardly extending lip on the open end of the holder and a rotatable ring also provided with a lip and so arranged that it can be shifted to an overlying position with respect to the lip of the body of the holder, so that a shade can be readily inserted in the holder and locked therein by turning the ring to a position where the lip thereof will be opposite to the lip on the body, whereby the shade will be gripped at diametrically opposite points and without the use of screws, as is necessary with the old type of holders in common use.

The invention has for its general objects to improve the construction of shade holders of the character referred to so as to be reliable and efficient in use, comparatively inexpensive to manufacture and so designed as to firmly grip lamp shades which may vary in size within certain limits.

A further object of the invention is the provision of novel stopping and locking means whereby the relative rotation of the ring and body of the holder is limited to a certain range, and whereby relative movement is prevented when the ring is in shade-holding position.

A further object of the invention is the provision of a plurality of springs arranged within the shade holder in such a manner as to engage the flange or rim of the shade and prevent rattling or vibration, it being understood that shades of a given size will vary within certain limits, and consequently the said springs are employed to compensate for variations in dimensions.

With such objects in view, and others which will appear as the description proceeds, the invention comprises various novel features of construction and arrangement of

parts such as will be set forth with particularity in the following description and claims appended hereto.

In the accompanying drawing, which illustrates one embodiment of the invention, and wherein similar characters of reference indicate corresponding parts in all the views,

Figure 1 is a side view of the shade holder with the clamping ring in open position so as to receive the shade; Fig. 2 is a bottom plan view of Fig. 1; Fig. 3 is a view similar to Fig. 1 but showing the clamping ring in shade-holding position; Fig. 4 is a bottom plan view of Fig. 3; Fig. 5 is a fragmentary view showing one of the spring gripping elements for the rim of the shade; Fig. 6 is a sectional view on the line 6—6, Fig. 5; and Fig. 7 is a perspective view of one of the spring gripping elements removed.

Referring to the drawing, A designates the shade holder body, which may be of any desired shape and constructed in any suitable manner. The bell-shaped body A has a cylindrical portion 1 at its bottom or open end, which cylindrical portion provides a shoulder 2 for the purpose of enabling the clamping ring B to be attached. This ring has an internal flange 3 on its inner edge which engages the shoulder 2, and it also has an internal flange 4 at its bottom edge to engage under the bottom edge 5 of the cylindrical portion 1 of the body A. By

means of these flanges 3 and 4 the ring is held against axial displacement and yet is free to rotate. The body A and ring B are provided respectively with inwardly-extending arcuate lips 6 and 7, which are integrally connected with the bottom edge of the cylindrical portion 1 of the body A and the bottom edge of the ring B respectively. These lips are so arranged that by turning the ring B one lip will overlie the other, as shown in Figs. 1 and 2, this position being the one which enables the shade C, Fig. 1, to be inserted in the holder. After the shade is entered, the ring B is turned half way around from the position shown in Figs. 1 and 2 to that shown in Figs. 3 and 4, so that the lips 6 and 7 will engage the flange or rim 8 of the shade C at diametrically opposite points. The opening movement of the ring B is limited by a lug

9 on the ring engaging a projection or lug 10 on the body A, as shown in Fig. 2, and the closing movement of the ring is limited by the projection 10 engaging one end of the lip 7, as shown in Fig. 4. Unlocking of the ring B is prevented by the interlocking stops or lugs 12 and 13 in the portion 1 of the body A and in the ring B. One of these parts, as, for instance, the portion 1, has an annular groove 15 in which the depression or stop 13 on the ring B freely moves. During the closing movement of the ring the stop or depression 13 engages the stop or bulge 12 in the groove 15, but by applying sufficient pressure to the ring B, the interlocking stops 12 and 13 will pass each other and assume the position shown in Fig. 4 and thereby prevent the ring B from unlocking or moving in an anti-clockwise direction.

20 The stop 10 by engaging the end of the lip 7 prevents travel of the ring B in a clockwise direction after the projection 13 snaps over the projection 12. There is sufficient resiliency in the metal of which the parts 25 are made to enable the projections 12 and 13 to pass each other. By this arrangement it can be seen that a positive pressure can be applied both in locking and unlocking the ring B.

30 In order to firmly hold the shade within the holder the cylindrical portion 1 of the latter is provided with a plurality of spring gripping elements D which are constructed as shown in Fig. 7. Each gripping element 35 comprises a base 16 from which extends a resilient bill 17 formed as a V-shaped member which has its side portions connected with the bars 18 of the base 16. These bars are curved at 19 to fit over the bead 20 which forms the groove 15 in the portion 1. 40 The gripping device is held in place by means of lugs 21 stamped out from the portion 1 and bent over the ends of the base 16, whereby the gripping element is held 45 against movement circumferentially of the portion 4. Movement at right-angles is prevented by means of the curved portions 19 of the bars 18 engaging the bead 20. In the present instance three of these spring gripping elements D are provided and they are 50 so located as to engage the rim 8 of the shade C. The bills 17 of the gripping devices will yield outwardly as the shade is inserted in the holder and will be maintained under tension, so that these devices 55 in combination with the lips 6 and 7 will firmly retain the shade and prevent vibration or rattling thereof in the holder.

From the foregoing description taken in 60 connection with the accompanying drawing, the advantages of the construction and method of operation will be readily understood by those skilled in the art to which the invention appertains, and while I have 65 described the device which I now consider

to be the best embodiment thereof, I desire to have it understood that the device shown is merely illustrative and that such changes may be made when desired as are within the scope of the appended claims.

Having thus described my invention, I claim as new and desire to secure by Letters Patent:

1. A shade holder consisting of relatively movable parts having shade-engaging and supporting means, and yielding means arranged to engage the shade and co-operate with the first-mentioned means for firmly gripping the shade, in combination with a shade having a rim externally engaged by 80 both of said means.

2. A shade holder comprising a body having shade-gripping and supporting means, and a plurality of yielding devices arranged within the body for gripping and firmly holding the shade against vibration, in combination with a shade having a rim externally engaged by said means and devices.

3. A shade holder comprising a body into which the rim portion of a shade enters, said holder consisting of relatively movable parts having rim-engaging lips, and a plurality of spaced spring gripping elements arranged to engage the rim of the shade, in combination with a shade having a rim engaged by 95 the said lips and the gripping elements.

4. A shade holder comprising a body having a shade-engaging lip, a ring rotatably mounted on the body and having a shade-engaging lip, and a plurality of elements 100 fixed within the body and having yielding portions engaging at a plurality of points the portion of the shade engaged by the lips.

5. A shade holder comprising a body having an open end into which the rim of a shade enters, an internal bead in the said body, a plurality of yielding gripping devices having portions shaped to fit the bead, means fixedly anchoring the devices on the body, and devices carried by the body for 110 engaging and supporting the shade.

6. A shade holder comprising a body open to receive the rim of the shade, shade supporting means on the body, an internal bead in the body, yielding devices for engaging 11 the shade rim and having base portions shaped to fit the bead to prevent movement of the devices transversely to the bead, and means for fastening the base portions of the devices to the body to prevent movement of 12 the devices parallel to the bead.

7. A shade holder comprising a body open to receive the rim of the shade, shade supporting means on the body, an internal bead in the body, yielding devices for engaging 13 the shade rim and having base portions shaped to fit the bead to prevent movement of the devices transversely to the bead, and means for fastening the base portions of the devices to the body to prevent movement of 14

the devices parallel to the bead, each device including a resilient portion disposed in outstanding relation to the base.

8. A shade holder comprising a body having a shade-engaging lip, a ring rotatably mounted on the body and having a shade-engaging lip, interlocking stops arranged on the body and ring in such position that one snaps over the other during the relative 10 turning of the ring and body to shade-holding position, and stop means for limiting the relative rotation of the ring and body to open or closed position of the ring.
9. A shade holder comprising a body, a ring on the body, shade-holding lips on the ring and body, stop means for limiting the opening and closing movement of the ring, one of the said parts having a circumferential groove with a stop or projection there- 20 in, and a stop or projection on the other

parts arranged to engage and snap past the other stop or projection to lock the ring in shade holding position.

10. A shade holder comprising a body section, a ring section rotatable thereon, one 25 section having a hollow bead provided with a stop, a stop on the other section, the stops being relatively yielding to permit them to snap by each other, additional stops on the sections arranged to engage each other when 30 the first stops pass each other, and shade holding means on the sections.

In testimony whereof I have signed my name to this specification in the presence of two subscribing witnesses.

FREDERICK REUTTER.
